**COMBINED BUMPER AND DUST COVER FOR
GASOLINE DISPENSING NOZZLE**

**George H. Sinclair, Richmond Heights, and
Wayne H. Rush, St. Louis, Mo.**

Application August 12, 1955, Serial No. 37,435

Term of patent 14 years

(Cl. D52—2)

FIG.1.

FIG.2.

FIG.3.

FIG.4.

Fig. 1 is a side elevational view of a combined bumper and dust cover for gasoline dispensing nozzle, embodying our new design, with a dispensing nozzle shown in broken lines for purposes of illustration.

Fig. 2 is a front elevational view of the bumper and dust cover,

Fig. 3 is a top plan view of the bumper and dust cover, and

Fig. 4 is an elevational view showing the back of our bumper and dust cover.

We claim:

The ornamental design for a combined bumper and dust cover for gasoline dispensing nozzle, substantially as shown and described.
